(57) **CLAIM**

I claim the ornamental design for a chain sprocket cover, as shown and described.

DESCRIPTION

FIG. 1 is a right perspective view of the chain sprocket cover; FIG. 2 is a right side view of the chain sprocket cover shown in FIG. 1; FIG. 3 is a left side view of the chain sprocket cover shown in FIG. 1;

FIG. 4 is a front view of the chain sprocket cover shown in FIG. 1;

FIG. 5 is a rear view of the chain sprocket cover shown in FIG. 1;

FIG. 6 is a top view of the chain sprocket cover shown in FIG. 1; and,

FIG. 7 is a bottom view of the chain sprocket cover shown in FIG. 1.

The subject matter shown in dashed lines, and any surfaces of the design not shown, including interior surfaces, form no part of the claimed.
